UNITED STATES PATENT OFFICE

EDGAR WILLIAM BRANDT, OF PARIS, FRANCE

BLADED PROJECTILE

Application filed November 5, 1930, Serial No. 493,675, and in France May 22, 1930.

This invention relates to improvements in bladed projectiles, and more particularly to a projectile of this type with a high specific capacity, intended to be projected by the aid of a discharging device preferably of smooth bore type.

The projectiles usually employed with said devices comprise substantially a body of suitable shape, terminated by a perforated tail 10 in which a propulsive cartridge is inserted, this latter being carried away by the projectile after percussion.

The idea has already occurred of stabilizing projectiles of this kind during their trajectory, by providing them on the rear end with fixed blades which act similarly to the feathering on an arrow.

These fixed blades, which can only have a very restricted periphery—limited by the 20 calibre of the discharging tube—operate in a zone of partial vacuum, and, for this reason, their efficiency is considerably reduced.

In order to obviate this inconvenience in the case of projectiles of small and medium 25 specific capacity, it has been proposed to give them a specially designed streamline shape, which minimizes the vortical zone at the rear of the projectile. As the result of this artifice, the fixed blades succeed in favourably 30 stabilizing the projectile during its trajectory.

In the case of projectiles of high capacity, however, this remedy is no longer applicable. In fact, in order to obtain said high capacity, 35 it has been necessary to increase the length of the projectile (since the calibre must remain unaltered) and to give it a shape assuring maximum volume, that is to say, in this particular case, cylindrical. Now the profile which has thus had to be adopted results in the formation, at the rear of the projectile 40 during its flight, of a vortical zone of far greater diameter than in the case of suitably designed profiles.

This drawback can evidently be remedied by increasing the length of the fixed blades, or by shifting them further to the rear by lengthening the tail, but this solution entails 45 increasing the volume of the combustion

chamber, thereby considerably diminishing the propulsive efficiency of the cartridge.

In contradistinction, the improvements forming the subject of the invention enable perfect stability to be obtained in the case of 55 any projectile whatsoever (more particularly, however, projectiles of high capacity) during flight, whilst obviating the drawbacks hereinbefore referred to.

According to an essential characteristic of 60 the invention, the rear of the projectile is equipped with blading, which is wholly or partially movable and is adapted to move automatically, when the shot is fired, from one stable position into the other, that is to 65 say, from a neutral (or folded) position, in which it is retained close to the body of the projectile in such a way as to cause a minimum of obstruction in the launching tube, into an operative (or unfolded) position 70 which, during flight, is situated at a distance from the body of the projectile and in a zone where it can exert a high stabilizing action.

The invention also comprises various devices which assure the actuation of the blading, at the desired moment, under the influence of one or more of the following agencies; air resistance, elastic members, the gas from the powder, the inertia of the blading 75 and the like.

The invention also comprises blocking devices (operating by springs, inertia or the like) which assure the retention of the blading in its neutral and operative positions respectively.

The invention also contemplates various designs of blading, intended to assure optimum stabilization, whilst permitting the introduction of additional charges for the purpose of strengthening the action of the propulsive 90 cartridge.

It follows from the foregoing characteristics that the projectile according to the invention can be stabilized in its trajectory under the most favourable conditions, even for 95 very high-angle fire, owing to the fact that the blading, when fixed in the operative position, operates in a zone of compression. It is thus possible, in accordance with the invention, to stabilize projectile of a far greater 100

total length, in calibres, than that of previous projectiles, and capable of attaining some ten calibres or more.

The destructive effect of projectiles of great length in calibres is well known to those engaged in the art.

Mention may be simply made of the fact that the projectiles according to the invention are admirably adapted for the destruction of objectives situated at a certain height above the ground, such as lines of barbed wire, which are mown down, by the fragments of the projectile, over a far greater area than with a shorter projectile.

15 The possibility of the high-angle firing of the projectiles according to the invention, is evidently a matter of interest in connection with the destruction of objectives in confined positions, or located behind nearly vertical obstacles, such as rock walls, and the like.

20 Other advantages and special features of the invention will become apparent from the following description.

In the accompanying drawings, which are 25 given solely by way of example:

Fig. 1 is an elevation of an embodiment of a projectile according to the invention, with the wings outspread;

Fig. 2 is a partial section on a larger scale; 30 Fig. 3 is a partial section, with the wings folded together;

Fig. 4 is a section along the line 4—4 of Fig. 2, looking towards the rear of the projectile;

35 Figs. 5 and 6 show modifications of the blading;

Figs. 7 and 8 represent an embodiment of the device for locking the blades in the closed and expanded positions respectively;

40 Fig. 9 is a modification of said device;

Fig. 10 is a detail of Fig. 2, on a larger scale;

Fig. 11 is a partial elevation and partial longitudinal section of a second embodiment 45 of the blading according to the invention, showing the wings spread out;

Fig. 12 is a partial end view and cross section along the line 12—12 of Fig. 11, with the wings spread out;

50 Fig. 13 is a partial elevation, showing the complete blading in the folded condition;

Fig. 14 is an end view of the blading of Fig. 13;

Fig. 15 is a section, along the line 15—15 55 of Fig. 13, of a detail of this blading, on a larger scale;

Fig. 16 is a partial axial section of a third embodiment of the blading, in the closed position;

60 Figs. 17 and 18 represent respectively an end view of this embodiment; and a detail of same, on a larger scale;

Fig. 19 is an elevation of the blading according to Fig. 16 in the operative position;

65 Fig. 20 is a longitudinal section of a dif-

ferent construction of the blading according to the invention, with the blades in the closed position; and

Fig. 21 is an end view of this blading.

As shown in Figs. 1 to 4, the projectile of 70 the invention comprises substantially a hollow body 1, of a generally ogivo-cylindrical shape, or of any other suitable form, and of a considerable length in calibres. This body, which is intended to receive the explosive, is 75 provided at the front end with a fuse 2 and, at the rear end, with a fluted band 3 of known type, which serves to centre the projectile in the launching tube, and limits the explosion chamber in front.

Towards the rear, the body 1 tapers at 4, preferably in the form of a truncated cone, the minor base of which is at the rear end. This portion is closed by a wall 5 (Fig. 2). The portion 4 terminates in a heel 6, to which is suitably attached a tubular tail 7, of known type, provided with a certain number of openings 8. This tail is intended to house the propulsive cartridge, the wall of which lodges in a groove 9 when the shot is fired.

At the rear end, the tail 7 is provided, on its periphery, with a certain number of pairs of lugs, such as 10 (Fig. 4), in which are pivotally mounted the axes, such as 11, of small blades, such as 12.

In the embodiment illustrated, each of these small blades is composed of an arm 13, provided with two integrally cast straight fins 14, 15 (Figs. 1-4) and a concavo-convex 100 terminal plate 16.

The fins 14, 15 are parallel to one another, and, when the blades are opened out, are parallel to the axis of the projectile, whereas, in that position, the medial axis A—A of the terminal plate 16 (Fig. 2) is slightly inclined 105 towards the front of the projectile.

A heel, such as 17 (Fig. 7), provided near the pivotal point of each blade 12 is designed so as to come in contact with the end of the tail, in order to retain the blade in the outspread or extended position.

When the blades are folded, the fins and terminal plates occupy the position shown in Fig. 3.

On issuing from the launching tube, the 110 blades move automatically from the position shown in Fig. 3 to that of Fig. 2, under the action of the resistance of the air and of the gases of the firing cartridge.

In the modification shown in Fig. 5, several 115 series of blades 18 are provided, each series being pivoted, at the forward end, on a shaft 19, carried, for example, by a fixed blade 20. Prior to firing, the blades are retained in folded position against the body of the projectile, either by hand or by suitable accessory means, against the action of a spring 21 which causes them to extend or spread out, like a fan, on issuing from the tube.

In the similar modification in Fig. 6, the 120

pivotal axis 22 is placed in the rear, which enables a widely projecting blading to be obtained in the extended or opened-out position 23.

5 It will be evident that the blades may be constructed in any suitable manner, such as stamping, welding, in one or more pieces, or the like. They may also be shaped in any form suitable for the parts they are to play.

10 In order to keep the blades in position, various devices may be employed, such as those hereinafter described.

In the embodiment shown in Figs. 7 and 8, a ball 24, actuated by a spring 25, housed in 15 a recess 26 in the blade, coacts with two notches 27, 28, corresponding respectively to the folded and extended positions.

The strength of the spring 25 and the form 20 of the notches 27, 28, are designed so that, on the one hand, they hold the blades firmly in the closed position, to prevent them from shaking, or from catching while the projectile is being handled, and, on the other hand, to prevent the blades, when opened out, from 25 folding up again when the projectile, fired at a high angle, begins to drop. They are also designed so as to allow the blades to be released, under the action of the air resistance, at the moment the projectile is 30 launched, and also as to enable a blade which has been locked in the opened position to be folded again by manual pressure.

In the modification shown in Fig. 9, the blades are retained in the closed and opened 35 positions, by means of a bent spring 29 adapted to engage in the notches 30 and 31 respectively.

The blades may also be held in the folded position, previous to firing, by means of a 40 locking ring 32 (Figs. 2 and 10) slidably mounted on the tail 7. This ring is provided with forward clips 33 which engage the plates 16 when the ring is retained in the locking position by arched springs 34, of suitable strength, engaging in a groove 35 in the 45 tail 7.

On the projectile being fired, the ring 32 recedes under the effect of inertia, and releases the blades.

50 By way of modification, the blades may be connected together by means of a suitable ligature 36 (Fig. 3) preferably of silk or other material capable of being burned by the combustion of the propulsive charge.

55 This ligature may be replaced by a spring (not shown) provided with a certain number of shallow notches corresponding to the edges, such as 37, of the arms of the blades.

The various components of the projectile 60 may be constructed of any suitable metal whatsoever, the body, for example, being of steel, and the wings of aluminium.

Figs. 11 to 15 represent another embodiment, in which the blades, such as 38, 39, of 65 cylindrical or other shape, are arranged to

pivot on axes, such as 40, 41, approximately parallel to the axis of the projectile. The axes 40, 41, which are preferably profiled in front (42, Fig. 11) to lessen their resistance to the air, are supported by rigid members, such as 43, 44, 45, suitably attached to the tail 7. Openings 46 provided in said members and in the blades, to the right of the perforations 8 in the tail 7, allow the powder gases to pass. A fusible ligature 47 (lead wire for example), preferably disposed on the front part of the tail, so as not to hinder the insertion of the cartridge, retains the blades in the folded position prior to firing, and, when the projectile is fired, disappears under the action of the heat generated by the deflagration of the powder gases. The heel pieces 49 serve also to hold the additional charges, such as 51, in the recesses between the blades and the tube. On issuing from 80 the tube, the blades, liberated in this manner, are forced, by springs 48, into the outspread or extended position represented in Figs. 11 and 12, in which their heel pieces 49 encounter the stops 50 by which the projectile 85 is guided in the tube (Figs. 12 and 15).

The blades are preferably arranged to fit one over the other, when in the closed position, (as shown in Figs. 14 and 15), above the supporting members, such as 43, 44. The whole, firmly supported against the tail 7, thus becomes extremely rigid and prevents any distortion of the blades, both in handling and under the effect of the deflagration of the cartridge, and of any additional 90 charges 51 that may be employed, irrespective of their number.

The maximum stabilizing surface is obtained by the special arrangement of the blades which, in the folded position, form two 100 superimposed layers, the stabilizing surface thus being approximately double the area of the exterior peripheral surface available.

The incurved form of the blades increases their resistance. The spring control enables the blades to open out without any sudden jolt. Moreover, the absence of any projection, and the uniform arrangement of the surface of the blades, assure to the projectile 110 the most favourable conditions of navigation 115 on its trajectory.

In the embodiment shown in Figs. 16 to 19, the blading is arranged so as to slide longitudinally and, on the projectile being fired, to move into a position beyond the vortical zone set up behind the projectile and in which the stabilizing forces acting on the blading do so with a greater amount of leverage.

With this object, the tail carrying the 120 blades is provided with an extension 52 (Fig. 16) suitably attached thereto, or integral therewith. This extension 52 is adapted to slide in a guide tube 53 centred in the axis of the projectile and is provided with a part 125

of larger diameter 55a at its forward end. Inside said guide tube is housed an intermediate member 54 (Fig. 18), slightly tapered at 55, intended to coact with the correspondingly shaped end 55 of the extension 52, so as to wedge it in the position shown in Fig. 19. A spring 56 bearing, on the one hand, against the bottom 57 of the tube 53, and, on the other, against the heel 58 of the tail 7, tends to push the latter backwards. A bolt 59, controlled by a spring 60, serves to lock the tail 7 in the position of Fig. 16, prior to firing.

When the projectile is fired, the gases of the cartridge escape by the openings 8, cause the bolt 59 to move inwards, and thus release the tail 7, which is then brought, by the spring 56, into the position shown in Fig. 19.

Although, in the example shown, the tail 7 is displaced by the action of a spring, it will be evident that any other suitable means could be employed for that purpose, such as the action of the powder gases, the resistance of the air, inertia, and the like.

The blades (Fig. 17) are preferably bent over at their outer edges 61, as shown, in order to increase their peripheral stabilizing action. They are also slightly inclined on the axis of the projectile, so as to set up a dragging effect under the most favourable conditions from the point of view of stability of flow. They are advantageously provided with ribs at 62 (Fig. 17), intended to increase the moment of inertia of the dangerous section of the blade, and with gaps 63 ensuring the equilibrium of the pressures. They are preferably rounded at their forward ends at 51a.

In the embodiment illustrated in Figs. 20 and 21, the sliding blading 64 moves rearwards, under the action of the inertia of its mass, at the moment of firing, in overcoming the resistance of the locking spring 65. The ailerons 66 stabilize chiefly by drag.

When the herein-described improvements are applied to aircraft bombs, the launching cartridge being suppressed, a suitable device, such as a spring, is employed in order to assist, if necessary, and conjointly with the resistance of the air, in setting the blades in operation at the moment the projectile leaves the launching tube or other device.

It is self-evident that the embodiments hereinbefore described are given solely by way of explanation and are in no respect restrictive, and that various modifications in detail may be introduced therein without departing from the spirit and scope of the invention as defined in the appended claims. Thus, in particular, the invention is by no means restricted to projectiles of high capacity, but can be equally applied to all other projectiles of any shape whatsoever, provided, or not, with a perforated tail.

Having now particularly described and

ascertained the nature of my said invention and in what manner the same is to be performed, I declare that what I claim is:—

1. A projectile comprising a body, pivots mounted at the rear of the body parallel to the longitudinal axis of the projectile and uniformly distributed about said axis, stabilizing wings each comprising a substantially rigid structure having the form when folded of a portion of an outwardly concave cylinder, two said wings being articulated on each said pivot and individually movable therearound between folded and extended positions, the said wings having in folded position a diameter less than and in extended position a diameter greater than the caliber of the projectile, a wing mounted on one of said pivots being in folded position in overlapping relationship with a wing of the adjacent pivot, the wings on each pivot moving in opposite angular directions about the pivot in passing from folded to extended positions, interengaging elements on each wing and on the body for limiting the extending movement of the wing, and means for moving the wings from folded to extended position upon firing of the projectile.

2. A projectile comprising a body, pivots mounted at the rear of the body parallel to the axis of the projectile and uniformly distributed about said axis, stabilizing wings articulated on the pivots and movable therearound between folded and extended positions, said wings having in folded position a diameter less than and in extended position a diameter greater than the caliber of the projectile, and leaving between them and a launching tube, when folded, recesses to accommodate propelling charges, and means for moving the wings from folded to extended position.

3. A projectile comprising a body, a perforated tubular tail fixed at the bottom of the projectile, a propulsive charge in the tail, pivots mounted on the perforated tail parallel to the axis of the projectile and uniformly distributed around said axis, stabilizing wings articulated on the pivots and movable therearound between folded and extended positions, said wings having in folded position a diameter less than and in extended position a diameter greater than the caliber of the projectile, and leaving between them and a launching tube, when folded, recesses to accommodate additional propelling charges, and means for moving the wings from folded to extended position.

4. A projectile comprising a body, a perforated tubular tail fixed at the bottom of the projectile, a propulsive charge in the tail, pivots mounted on the perforated tail parallel to the axis of the projectile and uniformly distributed around said axis, stabilizing wings articulated on the pivots and movable therearound between folded and ex-

tended positions, said wings having in folded position a diameter less than and in extended position a diameter greater than the caliber of the projectile, and leaving between them 5 and a launching tube, when folded, recesses to accommodate additional propelling charges, means to hold said additional propelling charges in said recesses, and means for moving the wings from folded to extended position.

5. A projectile comprising a body, a perforated tubular tail fixed at the bottom of the projectile, a propulsive charge in the tail, pivots mounted on the perforated tail 15 parallel to the axis of the projectile and uniformly distributed around said axis, stabilizing wings articulated on the pivots and movable therearound between folded and extended position, said wings having in folded 20 position a diameter less than and in extended position a diameter greater than the caliber of the projectile, and leaving between them 25 and a launching tube, when folded, recesses to accommodate additional propelling charges, elastic means for moving the wings from folded to extended position and cooperating abutment members on the wings and the body for retaining the wings in extended 30 position in opposition to the action of the said elastic means, the said abutments on the wings serving also to retain the additional propelling charges.

6. A projectile comprising a body, a perforated tubular tail fixed at the bottom of 35 the projectile, a propulsive charge in the tail, pivots mounted on the perforated tail parallel to the axis of the projectile and uniformly distributed around said axis, stabilizing wings articulated on the pivots and movable 40 therearound between folded and extended position, said wings having in folded position a diameter less than and in extended position a diameter greater than the caliber of the projectile, and leaving between them and a launching tube, when folded, recesses to 45 accommodate additional propelling charges, elastic means for moving the wings from folded to extended position, and cooperating abutment members on the wings and the body for retaining the wings in extended position 50 in opposition to the action of the said elastic means, the said abutments on the body serving also to guide the projectile in the firing tube.

7. A projectile comprising a body, pivots 55 mounted at the rear of the body parallel to the axis of the projectile and uniformly distributed about said axis, stabilizing wings articulated on the pivots and movable therearound between folded and extended positions, said wings having in folded position a diameter less than and in extended position a diameter greater than the caliber of the projectile, each wing comprising a substantially rigid structure having, when folded, 60 the form of a portion of an outwardly con-

cave cylinder, and means for moving the wings from folded to extended position.

8. A projectile comprising a body, a perforated tubular tail fixed at the bottom of the projectile, a propulsive charge in the tail, 70 pivots mounted on the perforated tail parallel to the axis of the projectile and uniformly distributed around said axis, stabilizing wings articulated on the pivots and movable therearound between folded and extended positions, said wings having in folded position a diameter less than and in extended position a diameter greater than the caliber of the projectile, the said wings resting on one another when folded and being further provided with 80 perforations opposite the perforations in the tail when the wings are folded, the wings leaving between them and a launching tube, when folded, recesses to accommodate additional propelling charges, and means for 85 moving the wings from folded to extended position.

9. A projectile comprising a body, a perforated tubular tail fixed at the bottom of the projectile, a propulsive charge in the tail, 90 pivots mounted on the perforated tail parallel to the axis of the projectile and uniformly distributed around said axis, stabilizing wings articulated on the pivots and movable therearound between folded and extended positions, said wings having in folded position a diameter less than and in extended position a diameter greater than the caliber of the projectile, and leaving between them and a launching tube, when folded, recesses to accommodate additional propelling charges, and locking elements for retaining the wings in folded position, said locking elements being released upon firing of the projectile. 100

10. A projectile comprising a body, a perforated tubular tail fixed at the bottom of the projectile, a propulsive charge in the tail, pivots mounted on the perforated tail parallel to the axis of the projectile and uniformly distributed around said axis, stabilizing wings articulated on the pivots and movable therearound between folded and extended positions, said wings having in folded position a diameter less than and in extended position a diameter greater than the caliber of the projectile, and leaving between them and a launching tube, when folded, recesses to 110 accommodate additional propelling charges, 115 disruptive ligatures connecting the wings and the perforated tubular tail for retaining the wings in folded position; said ligatures passing through the said perforated tubular tail and being disrupted upon the firing of the charge, and means for extending the wings after disruption of the said connecting ligatures. 120

11. A projectile comprising a body, pivots mounted at the rear of the body substantially parallel to the axis of the projectile and dis- 125

tributed about said axis, stabilizing wings articulated on the pivots and movable there-around between folded and extended positions, said wings having in folded position a diameter less than and in extended position a diameter greater than the caliber of the projectile, each wing comprising a substantially rigid structure presenting, when in folded position, an outwardly open recess, and means for moving the wings from folded to extended position.

10. 12. A projectile comprising a body, pivots mounted at the rear of the body substantially parallel to the axis of the projectile and distributed about said axis, pairs of stabilizing wings jointed on each said pivot, the wings of each pair being movable about the common pivot for said pair in opposite angular directions between folded and extended positions and having in folded position a diameter less than and in extended position a diameter greater than the caliber of the projectile, each wing comprising a substantially rigid structure presenting, when in folded position, an outwardly open recess, and means for moving the wings from folded to extended position.

15. 13. A projectile comprising a body, pivots mounted at the rear of the body substantially parallel to the axis of the projectile and distributed about said axis, pairs of stabilizing wings jointed on each said pivot, the wings of each pair being movable about the common pivot for said pair in opposite angular directions between folded and extended positions and having in folded position a diameter less than and in extended position a diameter greater than the caliber of the projectile, and an individual torsion spring surrounding each said pivot and operating upon both the wings of the pair thereon for moving the wings from folded to extended position.

20. 25. In testimony whereof, I affix my signature.
EDGAR WILLIAM BRANDT.
